UNITED STATES PATENT OFFICE.

BENJAMIN ADRIANCE AND AMOS CALLESON, OF BROOKLYN, NEW YORK; SAID CALLESON ASSIGNOR TO SAID ADRIANCE.

BOTTLE-CAPPING MACHINE.

1,042,068.

Specification of Letters Patent.

Patented Oct. 22, 1912.

Application filed February 5, 1910. Serial No. 542,297.

To all whom it may concern:

Be it known that we, BENJAMIN ADRIANCE and AMOS CALLESON, citizens of the United States, residing in Brooklyn, borough of Brooklyn, and State of New York, have invented a certain new and useful Improvement in Bottle-Capping Machines; and we do hereby declare the following to be a full, clear, and exact description of the invention, 10 such as will enable others skilled in the art to which it appertains to make and use the same, reference being had to the accompanying drawings, and to letters of reference marked thereon, which form a part of this 15 specification.

Our present invention relates to means for conducting bottle-caps or the like articles from a suitable source of supply in which they are indiscriminately disposed in quantity 20 to the point where they are to be mechanically associated with other parts, such as bottles, and for insuring the articles being properly faced when they reach such point.

Our principal objects are to simplify the construction and cheapen the cost of manufacture of such mechanisms; to insure regular and reliable coöperation of the various parts thereof to the end that the articles 30 being operated upon may be transmitted from the source of supply to the point where they are to be delivered in as rapid sequence as the circumstances may require and with as little likelihood of jamming or clogging 35 as possible; and to render the mechanism practically completely automatic in operation, so that the attendant has no further care in connection therewith than merely to keep the supply replenished.

Our invention consists in a novel construction of so much of a mechanism of the kind indicated as includes a hopper or the like for the articles, means for promoting their delivery therefrom and means for insuring their being properly faced when they 40 reach the point where they are to be operated upon; and in a novel combination of a chute for conducting the articles to the point where they are to be operated upon and means for insuring the advance of the articles in orderly sequence into their correct position at the said point.

The invention is fully illustrated in the accompanying drawings, wherein,

Figure 1 is a side elevation of a bottle-

sealing machine provided with our improvements; Fig. 2 is a front elevation, on a somewhat larger scale, of the hopper, chute and sealing head and accessory mechanism, certain parts appearing in section; Fig. 3 60 is a side elevation of what is seen in Fig. 2, certain parts being omitted; Fig. 4 is an underneath plan view of the lower end of the chute; Fig. 5 shows in side elevation the main actuating rod and the means attached thereto for keeping the articles advanced 65 in the chute to the delivery point; Fig. 6 shows the hopper and a fragment of the chute in side elevation, certain parts being broken away and others appearing in section; Fig. 7 is a substantially central vertical sectional view through the hopper and chute shown in Fig. 6; Fig. 8 is a side elevation of a certain rotary disk appearing in Figs. 2, 3, 6 and 7; and Figs. 9 and 10 70 75 are front and side elevations (the latter appearing partly in section) of the means for transmitting motion to a certain rod *g*.

a designates the frame of the machine; *b* a horizontal shaft journaled therein; *c* a 80 pulley or the like, adapted to be suitably driven, rotating freely on said shaft; *d* a clutch, controlled by a lever *e*, whose construction and mode of operation it is not necessary herein to particularly describe 85 further than to say that on each actuation of said lever a single complete rotation is transmitted to the shaft, unless the lever is held where moved, in which case the synchronous rotation of the shaft and pulley is maintained; *f* a crank-disk on the front end of said shaft; *g* a vertically sliding spindle suitably guided in the frame and carrying the bottle-rest *h*; *i* a thrust-block bottled or otherwise secured to the lower end of the spindle and having at the back thereof a horizontal guide-way *j*; and *k* a block sliding in the guide-way of the thrust-block and receiving the crank-pin *l* on crank-disk *f*. 90 95

The crank-disk, the lower end of the spindle and the above-described parts whereby a reciprocating motion is transmitted to the spindle from the crank-disk are inclosed within the housing *a'* of the frame *a*.

m is an arm which is attached to the block *i* by screws or the like *n* and projects through an opening *o* in the housing *a'*; to to this arm is connected, by a bolt *p* or otherwise, the aforesaid actuating rod *q* which will be again referred to. *r* is merely a 100 105 110

plate arranged to cover the opening o , the same being secured to the arm m .

The frame a comprises a standard a^2 whose upper end terminates in a clamp a^3 having a bolt or the like a^4 for contracting said clamp into gripping relation with the stem a^5 of a sealing head a^6 of any desired type. The upper end of the stem protrudes from the clamps a^3 and receives a clamp s formed on the lower end of an upright t , the clamp being contracted into gripping relation with the stem by a bolt u . Secured to the upper end of the stem is a safety collar a^7 .

v is a hollow casting open at its front (which corresponds to the right side of the machine) and at the top. The bottom of this casting is rounded, as at w , and it follows substantially the shape of a cone, its greater radius being at the front; the middle portion of the bottom w is a channel w' also following substantially the form of a cone, though of less diameter than the first, the greater radius of said channel being at the front. The lower portion of said casting is a depending substantially semi-circular flange x formed with a flat base or seat y which may be bolted or otherwise secured on a similar seat z on the upper end of the upright t . Against the front open side of the casting v is secured a plate 1 having a forwardly projecting hub 2 whose axis is concentric with the arc 3 representing the line of juncture between the front face of the flange x and the curved surface of the channel w' ; the lower portion 4 of the plate 1 is semi-circular in form, though of less radius than that of the flange x with relation to which it stands spaced. A forwardly projecting rib 5 is formed on the flange x and against this is secured a semi-circular strip 6 with relation to which the portion 4 of the plate 1 is spaced, forming a semi-circular slot 7. The slot 7 and a series of holes 8 arranged in a semi-circular row in the portion 4 of the plate 1 permit visual inspection of the progress of the caps in the channel or space formed between the portion 4 of the plate 1 and the front face of the flange x .

It will be understood that the parts v and 1 constitute a hopper, the opening at the top of which may be closed by a hinged cover v' .

The front face of the flange x has a semi-circular groove 9 following the arc of a circle described about the axis of the hub 2, the same being therefore concentric with the arc 3 but of greater radius, so that its ends terminate at the arc 10 which corresponds to the edge formed between the curved surface of the bottom w of the casting v and the interior face of its flange x . The deepest part of the groove 9 is at its outer perimeter. Mating with the groove 9 and formed on the back of the portion 4 of the plate 1 is a

cross-sectionally curved rib 11 which coincides in length with the length of the groove 9. This groove and rib coact with each other in such manner as to permit a cap falling down between the front face of flange x and the portion 4 of plate 1 to pass with freedom if the concave side of the cap is faced forwardly; if it is faced rearwardly, the cap will be checked, its flange-edge resting in the deep part of the groove 9. A clear understanding of this part of the apparatus may be obtained from our U. S. Patent No. 913,182.

Those caps which pass the coacting rib and groove either fall directly through the centrally located passage 12 formed in the rib 5 or else come to rest on said rib, along which they temporarily roll until by gravity they successively fall through said passage. Those caps which are rejected, i. e., which cannot pass the coacting groove and rib because they are improperly faced, are rolled along the deep part of the groove 9 upwardly and discharged back into the body of the hopper.

In order to agitate the caps in the hopper and prevent them from clogging at the entrance from the body of the hopper to the space formed between flange x and plate 1, and in order to return the rejected caps into the body of the hopper so that they will not obstruct said space and prevent the caps properly faced from passing therethrough, the following mechanism is provided: To a shaft 13 journaled in the hub 2 is fixed a disk 14 having a rearwardly extending fin or blade 15 whose lower edge 16 is formed at the same angle relatively to its axis as the angle represented by the bottom of the channel w' in the cross-section of the hopper, as seen in Fig. 7; the fin has a downwardly extending finger 17 which projects between the groove 9 and rib 11. The shaft 13, together with the disk, oscillates, and its oscillatory or rocking motion may be limited by a stud 18 formed on the front of the disk and penetrating an arc-shaped slot 19 formed in the portion 4 of plate 1 concentrically with the arc 3. In order to prevent caps or other objects from falling between the disk 14 and plate 1, which are spaced so as to reduce friction, as shown in Fig. 7, an arc-shaped overhanging ledge 20 is formed on the plate 1 being, in effect, a continuation of the rib 11. As the disk oscillates its fin or blade 15 moves the caps held by gravity against the disk and on the advancing side of its fin away from the lowest portion of the channel w' , other caps descending to take their places. Thus massing of the caps at the outlet, with a consequent retard and possible checking of their escape into the outlet, is avoided, and at the same time those caps which are checked by the outlet are cleared away (returned in the

present instance to the hopper) so as to leave the way through said outlet unobstructed by them.

21 is a pinion formed exteriorly of a sleeve 5 22 which is journaled on the hub 2; the pinion is inclosed in a guard 23 attached to the plate 1. The portion of shaft 13 which protrudes from the hub is reduced, as at 24, and splined thereon are two metal disks 25 10 between which is arranged a friction disk of fiber or the like 26, the latter being secured in the end of the sleeve 22 by the pins 27. The disk 26 is held pressed between the disks 25 by a spiral spring 28 coiled between the outer disk 25 and an adjusting nut 29 on the reduced end of the shaft 13. The upper end 15 of the rod *q* is formed as a rack 30 which meshes with the pinion 21. When this rack is reciprocated and the pinion thereby oscillated the disk 14 will be also oscillated; and although the advance of the disk under the impulse of the rod *q* may be limited against further movement (either by the stud 18 engaging one end of the slot 19 or by the disk 25 becoming jammed by the caps) before rod 30 has completed its movement, no damage can occur owing to the slip-friction-grip transmission means afforded by the disks 25 and 26. Rod *q* is kept engaged with the pinion by a guide 31 suitably secured to the front of the plate 1.

The front of the upright *t* is formed with a vertical groove 32 which coincides with the passage 12; secured to the upright *t* in 35 overlapping relation to the groove 32 are the spaced strips 33. Thus a chute is formed through which the caps descend in succession upon falling through the passage 12.

The lower end-portion 34 of the chute 40 forms a part of a detachable casting comprising a socket 35 which is fitted over the sealing-head *a*⁶ from below, the casting being held in place by a hook 36 carried by the upright *t* and engaging a pin 37 on the 45 casting. The caps passing down the chute successively enter the socket 35 and upon entering said socket each is supported by an annular ring 38 whose opening 39 is designed to admit the neck of the bottle, said 50 ring being hinged to the casting and adapted to be held in its normal position by a latch 40.

On the rod *q* is a finger 41 having a vertical slot 42 and secured to the rod *q* by a 55 screw 43 penetrating said slot. This finger is designed to ensure the advance of the lowermost cap to a position where it is properly disposed in the socket preliminarily to the sealing operation, and to this end it is 60 normally held projecting into the chute, which is open from top to bottom thereof.

In order to retain the finger in its working position, and particularly to cause it to follow the curvature of the chute in the portion 65 of the latter, and also in order to

cushion the finger should the advance of the caps thereby be positively prevented for any reason, a spiral spring 44 is made to connect an outwardly projecting arm 45 on the top of the finger with a pin 46 on the 70 rod, the slot 42 allowing the incidental upward movement of the finger at this time. An inclined shoulder 47 is formed on the finger and adapted to wipe against a block 48 attached to the front of the chute as the 75 finger approaches its upward limit of movement with the rod *q*, so that the finger withdraws from the chute at this time to allow the caps above it in the chute to feed down without obstruction. In a block 49 attached 80 to the front of the chute is pivoted a lever 50 one end of which is connected by a spring 51 with a stud 52 on the upright *t* and on the other end of which is secured, by a set screw 53, a spring arm 54 whose upper end 85 55 is bent rearwardly, entering the slot 7. On the rod *q* is a pin 56 which, when the rod descends, engages the right-hand end of the lever 50 in Fig. 3 from above, moving the lever suddenly on its fulcrum and hence 90 causing the spring arm 54 to move quickly to the right; when the rod *q* again rises the spring causes the return of the arm 54. According as this arm is at one or the other of its limits of movement, so it holds back the 95 row of caps at one side thereof waiting to pass out the passage 12 and leaves said passage clear for the row of caps waiting to enter said passage at the other side of the arm; without it, two caps meeting over the 100 passage 12 are likely to obstruct said passage, especially if the caps are of the corrugated flanged type and are therefore likely to interlock with each other. As the sudden movements of the arm 54 might 105 occasionally return to the body of the hopper, caps which had already passed between groove 9 and rib 11, steps 57 are disposed between the plate 1 and flange *x* at the ends of the groove 9 and ribs 5.

The general operation of the improved mechanism herein described will be at once apparent to those skilled in this art in view of the foregoing description of the operations of the several organisms thereof.

Having thus fully described our invention, what we claim is:

1. The combination, with a receptacle having a depression in its bottom and a relatively elongated outlet for the articles extending across said depression, of an agitating member inclosed and movable within the receptacle and having a part thereof received by the outlet, substantially as described.

2. The combination, with a receptacle having a depression in its bottom and a relatively elongated outlet for the articles extending across said depression, of a blade-shaped agitating member movable within 130

4
said depression crosswise of itself and having a projection received by said outlet, substantially as described.

5 3. The combination of a supply means comprising a receptacle having an outlet for the articles, and an agitating blade movable crosswise of itself in said receptacle and over said outlet and having a projection received by the outlet, substantially as described.

10 4. The combination of a supply means comprising an outlet and a non-continuous fixed checking shoulder within said outlet having one end directed toward the interior of the supply means, said shoulder being 15 adapted to allow free passage of the articles through said outlet when the same are properly faced and to arrest said article when improperly faced, and means for advancing the articles checked by said shoulder along 20 the latter into the interior of the supply means, substantially as described.

25 5. The combination, with walls to support the articles spaced from each other to form a discharge passage and sloping toward each other, a checking member movable back and forth over said passage from a position at one side of and unopposed to said passage to a position at the other side of and likewise unopposed to said passage, and means for 30 effecting the back and forth movements of said member, substantially as described.

6. The combination of substantially converging walls spaced at their adjoining ends to form a passage and adapted to support

35 the articles, a guideway communicating with said passage, a reciprocating means operating to positively advance the articles in the guideway and an oscillating pivoted member controlled by said reciprocating member and controlling the admission of the articles to said passage, said pivoted member having 40 a portion thereof projecting opposite said

passage at the relatively inner side thereof and movable back and forth across the same, substantially as described.

45 7. The combination, with a guide-way for the articles, of means for advancing the articles in the guide-way comprising a member reciprocating in the direction of the length of the guideway, a part to engage the articles movable with said member and backwardly yielding with respect thereto and a cushioning means interposed between said part and said member, substantially as described.

50 8. The combination, with a guideway for the articles, of means for advancing the articles in the guideway, comprising a member reciprocating in the direction of the length of the guideway, a part movable in said member toward and from the guideway, and normally held toward the same, and means, disposed in the path of movement of said part, for effecting its withdrawal from the 55 guideway, substantially as described.

55 9. The combination, with a guideway for the articles, of means for advancing the articles in the guideway comprising a member reciprocating in the direction of the length of the guideway, a part pivoted in said member and normally held toward the guideway, and a part disposed in the path of movement of the first part and adapted to effect the withdrawal thereof from the guideway, 60 substantially as described.

65 In testimony, that we claim the foregoing, we have hereunto set our hands this 2nd day of February, 1910.

BENJAMIN ADRIANCE.
AMOS CALLESON.
